UNITED STATES PATENT OFFICE.

WALTER F. KOKEN, OF ST. LOUIS, MISSOURI.

SEAT-FRAME FOR BARBER-CHAIRS.

1,337,609.

Specification of Letters Patent. Patented Apr. 20, 1920.

Application filed March 31, 1919. Serial No. 286,355.

To all whom it may concern:

Be it known that I, WALTER F. KOKEN, a citizen of the United States, residing at St. Louis, Missouri, have invented a certain 5 new and useful Improvement in Seat Frames for Barber-Chairs, of which the following is a full, clear, and exact description, such as will enable others skilled in the art to which it appertains to make and use 10 the same.

This invention relates to chairs of the kind that are used by barbers, dentists and other specialists, and particularly to barber chairs of the type which are provided with 15 a metal seat frame.

The metal seat frames that have heretofore been used on barber chairs were formed either by one large, heavy casting or a cast metal spider combined with a cast metal 20 member that formed the exterior portion or exposed portion of the seat frame. Metal seat frames of the character referred to are exceptionally heavy and are costly to manufacture on account of the large amount of 25 machine work required in boring holes in the casting and in grinding off the outer surface of the casting preparatory to finishing it in porcelain enamel.

The object of my invention is to provide 30 a seat frame for barber chairs, dentist chairs and the like that is light in weight and inexpensive to manufacture.

To this end I have devised a seat frame that is composed of a supporting structure 35 formed preferably of wood and a sheet metal shell that incases said supporting structure and forms the exterior or exposed portion of the seat frame.

Figure 1 of the drawings is a vertical 40 transverse sectional view of a seat frame for barber chairs and the like constructed in accordance with my invention, said view being taken approximately on the line 1—1 of Fig. 2; and

Fig. 2 is a top plan view of a portion 45 of said seat frame.

Referring to the drawings which illustrate the preferred form of my invention, A designates the pedestal base of a barber 50 chair and B the vertically-adjustable stem that carries the seat frame of the chair. The seat frame comprises a supporting structure of skeleton design formed prefer-

ably by a horizontally disposed wooden member 1 secured to the stem B, a plurality 55 of transversely-disposed wooden members 2 (only one of which is shown in Fig. 2) arranged at right angles to the member 1 and connected to same by screws 3 or other suitable fastening devices, and a plurality 60 of rim pads or sections 4 mounted on the members 2 and secured to same in any suitable manner. The exterior or exposed portion of the seat frame is formed by a sheet metal shell composed of a horizontally- 65 disposed plate 5 mounted on the pads or sections 4 of the supporting structure and a sheet metal skirt member 6 that surrounds said plate and projects downwardly from same far enough to conceal the members 1 70 and 2 of the supporting structure. The plate 5 is provided at its inner edge with a downwardly turned portion or depending flange 7 that laps over the inner edge of the sections 4, and said plate projects laterally 75 some distance beyond the outer edge of said sections and is bent downwardly and inwardly so as to form a bead 8. The skirt member 6 of the shell is provided at its upper edge with an inwardly-projecting 80 flange 6^a that is preferably set into recesses or grooves in the sections 4, said skirt member 6 being secured to the supporting structure preferably by screws or other suitable fastening devices 9, as shown 85 in Fig. 1. The lower edge of the skirt member 6 is bent to form a bead 10.

A seat frame of the construction above described is light in weight, as it is composed of a supporting structure of skeleton 90 form incased by a sheet metal shell that forms the exterior of the seat frame. Furthermore, such a seat frame can be manufactured at a low cost, owing to the fact that the sheet metal shell of same can be 95 formed in a die press and can be finished in porcelain enamel without the necessity of first grinding off the surface of same that is to be coated with enamel.

Having thus described my invention, what 100 I claim and desire to secure by Letters Patent, is:

1. A seat frame for barber chairs and the like composed of a supporting structure, a sheet metal skirt member surrounding 105 said supporting structure and depending

from same, and a sheet metal plate mounted on said supporting structure and projecting laterally over the upper edge of said skirt member.

- 5 2. A seat frame for barber chairs and the like composed of a skeleton supporting structure formed by a plurality of wooden

members, and a sheet metal shell incasing said supporting structure and composed of a vertically-disposed skirt member, and a horizontally-disposed top plate whose peripheral edge is bent to form a finishing bead that surrounds said skirt member.

WALTER F. KOKEN.
